BENDING MACHINE

Victor H. Van Sant, Newark, N. J., assignor to
 Federal Telephone and Radio Corporation, New
 York, N. Y., a corporation of Delaware

Application April 28, 1945, Serial No. 590,887

15 Claims. (Cl. 153—25)

1

This invention relates to a machine for bending rods, wire and similar sections, and particularly, for example, lead-in wire for vacuum tubes.

It is an object of the invention to provide a machine for simultaneously producing a double bend in a rod or wire by means of a machine having a double slide of which one slide is movable in one direction and the other is movable in a direction at right angles thereto. A further object of the invention resides in the provision of a connecting link pivotally secured to one of the slides to exert a pull thereon at an angle to the movements of both slides. Another object resides in the provision of means to heat, preferably by electric resistance, and before the bending operation, that part of the wire which is to be bent.

The machine thus aims to provide a slide which is so mounted that it is capable of moving either in a vertical or horizontal direction or both, or at any angle determined by the desired bend to be imparted in the rod. Another object resides in the provision of means for adjusting the extent of movement of the slides.

Further objects will be apparent from the following description when considered in connection with the accompanying drawings in which,

Figure 1 is a plan view of the wire bending machine showing the position of the parts just before the bending operation,

Fig. 2 is a plan view of the machine showing the position of the parts after completion of the bending operation,

Fig. 3 is a cross sectional view of the machine taken on line 3—3 of Fig. 1 in the direction of the arrows, and

Fig. 4 is a cross sectional view of the machine taken on line 4—4 of Fig. 1 in the direction of the arrows.

The machine illustrated by way of example includes a base frame or plate 10 having a square or rectangular slideway 11 provided therein defined by side faces or surfaces 12 and 13. The base frame has a pair of upstanding lugs 14, one adjacent each side face 12 and each lug has a threaded hole therein to receive adjustable stop bolts 15 and 16, the purpose of which will be explained.

A rectangular main slide plate or member 17 is slidably mounted in the slideway 11 in the direction of the arrows and guided by the side faces 13. As will be seen from Figs. 1 and 2, the slide plate 17 has a length just sufficient to contact the side faces 13 but the width is narrower than the length of the faces 13 so that

2

the slide plate 17 will reciprocate from right to left and vice versa toward the faces 12. The slide plate 17 is provided with a rectangular slideway 18 defined by side faces or surfaces 19 and 20 and this slideway 18 is provided with an auxiliary slide plate or member 21. The slide plate 21 is slidable in the direction of the arrows which is at right angles relative to the reciprocating movement of the slide plate 17 and such sliding movement is guided by the side faces 20 toward the side faces 19.

An adjustable stop bolt 22 is threaded in the slide plate 17 against which the slide plate 21 abuts during the bending operation.

15 The slide plate 21 is provided with a pivot pin 23 to which a connecting link 24 is secured which operates the slide plates. This link has one end of the spring 25 secured thereto by pin 26, the other end of the spring being secured to a pin 20 secured in the base frame 10. The slide plate 21 is also provided with a pair of clamping jaws 28 and 29 of which jaw 28 is stationary but jaw 29 is slidable in a slot 30. A cam 31 contacts the jaw 29 to adjust it against the work and thus 25 securely hold the work between the jaws.

Another pair of clamping jaws 32 and 33 are mounted on the base frame 10 of which jaw 32 is stationary but jaw 33 is slidable in a slot 34. A cam 35 is pivotally mounted to 30 adjust the jaw 33 toward the work to thereby clamp the work between the jaws.

On the drawings the work is indicated by a wire or rod 36 which is clamped in the jaws 28, 29, 32 and 33. In order to provide for the resistance heating of the rod 36 in its length between the jaws, the latter are suitably insulated from each other and from the frame 10 and slides 17 and 21 and the rod may also be insulated by any suitable means such as an insulation strip, 40 not shown, provided under the wire and on the parts of the machine. Wires 37 and 38 carry electric current to the jaws 28 and 32, the latter of which are preferably made of copper.

The machine operates as follows:

45 The wire 36 is clamped between both jaws 28, 29 and 32, 33 by means of the cams 31 and 35 to hold the wire securely in the machine. The electric current is then turned on by any suitable switch, not shown, to heat the wire by resistance 50 in that portion of its length which is between the jaws and which is to be bent. After heating the wire to a desired degree, such for instance where it becomes almost incandescent, the connecting link 24 is pulled in the direction indicated by its arrow, by means of a pneumatic

plunger, not shown, whereby the jaws 28 and 29 are moved relative to the jaws 32 and 33. Both slides 17 and 21 may move simultaneously in the direction indicated by their arrows at right angles relative to each other or the auxiliary slide 21 may move first until its abuts against the stop bolt 22 and then the slide plate 17 moves to the left until it abuts against the stop bolt 16. Thus when slide 21 moves first and then slide 17 the movement of slide 21 determines the offset in the wire. Furthermore the slide 21 is capable of moving either vertically or horizontally or at any angle determined by the desired bend in the rod.

The duration of the heating time for the rod 36 may be controlled by a time switch, not shown, and the time switch in turn may operate the pneumatic plunger for the link 24 to produce the bending operation.

After the bending operation, Fig. 2, the wire is removed from the machine by operation of the cams 31 and 35 and the spring 25 will move the parts back to the initial position shown in Fig. 1.

The machine is of course capable of various modifications within the scope of the invention and the appended claims. For instance the slides 17 and 21 may have any desired thickness and both slides may have the same thickness so that the slide 21 will contact the surface of the slideway 11. It would also be possible to provide the slideways 11 and 18 and the slides with tongue and groove slide surfaces in order to securely maintain the parts in their working positions during the bending operation.

I claim as my invention:

1. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, and single means connected to the auxiliary slide plate to reciprocate both slide plates in their respective slideways during the bending operation.

2. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, and one jaw of each pair being movable toward and away from its respective other jaw, means for clamping the movable jaw against the wire, and single means connected to the auxiliary slide plate to reciprocate both slide plates in their respective slideways during the bending operation.

3. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, and one jaw of each pair being movable toward and away from its respective other jaw, means for clamping the movable jaw against the wire, single means connected to the auxiliary slide plate to reciprocate both

slide plates in their respective slideways during the bending operation, and spring means connected to the slide reciprocating means and the base frame to return the slides to their initial positions after the bending operation.

4. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, and one jaw of each pair being movable toward and away from its respective other jaw, cam operated means for clamping the movable jaw against the wire, and single means connected to the auxiliary slide plate to reciprocate both slide plates in their respective slideways during the bending operation.

5. A machine for bending wire and the like comprising a base frame, a first slide member slidably mounted on said frame adapted to move parallel to the axis of the material to be bent, a second slide member slidably mounted on said first slide member, adapted to move thereon in a direction perpendicular to the movement of said first slide member, means attached respectively to said base frame and said second slide member to clamp the material to be bent, and single means to reciprocate said slide members, said first slide member regulating the angle of bend and said second slide member regulating the offset of the material to be bent.

6. A machine for bending wire and the like as claimed in claim 5, wherein said single means to reciprocate said slide members is pivotally connected to said second slide member.

7. A machine for bending wire and the like as claimed in claim 6, wherein said single means to reciprocate said slide members comprises a single link connected to said second slide member movable at an angle relative to the movements of both slide members to reciprocate the latter during the bending operation.

8. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, single means connected to the auxiliary slide plate to reciprocate both slide plates in their respective slideways during the bending operation, and stop bolts mounted on the frame to limit the movement of the main slide plate in its slideway this limitation of movement being of accurately predetermined degree.

9. A machine for bending wire and the like comprising a base frame having a slideway therein, a main slide plate mounted in said slideway and having a slideway therein, an auxiliary slide plate mounted in the slideway of the main slide plate, a pair of jaws mounted on the base frame, a pair of jaws mounted on the auxiliary slide plate, said pairs of jaws being adapted to clamp the wire on the machine, single means connected to the auxiliary slide plate to reciprocate both slide plates in their respective slideways during the bending operation, stop bolts mounted on the frame to limit the movement of the main slide plate in its slideway, and a stop bolt in the main slide plate to limit the movement of the auxiliary

slide plate in the main slide plate said stop bolts on said frame and said main slide plate being accurately and continuously adjustable to the end that said wire and the like may be doubly bent with accuracy when said wire and the like has a short length.

10. A machine for bending wire and the like comprising a base frame having a rectangular slideway therein and a pair of clamping jaws, a main slide plate contacting two opposite sides of the slideway to slide thereon in one direction with clearance on the two other opposite sides of the slideway, said slide plate having a rectangular slideway therein, an auxiliary slide plate slidably mounted in the slideway of the main slide plate in contact with two opposite sides thereof and in a direction at right angles relative to the movement of the main slide plate, said auxiliary slide plate having a pair of clamping jaws therein which with the first-mentioned pair of clamping jaws secure the wire in the machine, and single means for exerting a pulling force on the auxiliary slide plate at an angle relative to the directions of movement of both slide plates during the bending operation.

11. A machine according to claim 10, in which the pulling force means is in the form of a single connecting link pivotally secured to the auxiliary slide plate.

12. A machine for bending wire and the like comprising a base member having a slideway therein, a first slide plate movably mounted in the slideway of said base member, said slide plate having a slideway therein and being adapted to move parallel to the axis of the material to be bent; a second slideplate movably mounted in the slideway of said first slide plate and being adapted to move in a direction at right angles to the direction of the movement of said first slide-plate, and means attached respectively to said base member and said second slideplate, for holding a wire on said machine and for maintaining

the end portions of the wire in fixed angular relation to said base and said second slide member, and single means for causing movement of said first slideplate to regulate the angle of bend, and movement of said second slideplate to regulate the offset of the material to be bent.

13. A machine for bending wire and the like as claimed in claim 12, wherein said single means for causing movement of said slideplates exerts a pulling force on one of said slideplates in an angular direction relative to the directions of movement of said slideplates for the bending operation.

14. A machine for bending wire and the like as claimed in claim 12, wherein a plurality of stop members are adjustably mounted in the base member to adjust and limit the movement of said first slideplate.

15. A machine for bending wire and the like, as claimed in claim 12, wherein a stop member is adjustably mounted in the first slideplate to adjust and limit the movement of said second slideplate.
